UNITED STATES PATENT OFFICE

WILLIAM R. TWIFORD AND GEORGE OEHLER, OF MIAMI, FLORIDA

DOG-RACING APPARATUS

Application filed March 26, 1927. Serial No. 173,736.

Our invention relates to an amusement device including a race track and a mechanical rabbit which is caused to travel in a way to maintain its position ahead of a pack of racing dogs.

The general object of our invention is to provide novel means for carrying and causing the rabbit to travel.

A further object is to provide a novel trap 10 into which the rabbit is caused to disappear.

A more specific object of the invention is to provide a mechanical racing rabbit with overhead carrying means.

The nature of our invention and its distinguishing features and advantages will clearly appear as the description proceeds.

Reference is to be had to the accompanying drawings forming a part of this specification, it being understood that the drawings are 20 merely illustrative of one example of the invention.

Figure 1 is a diagrammatic plan view of a race track equipped with our invention.

Figure 2 is a detail in sectional plan view, 25 given to show the trap.

Figure 3 is a perspective of the trap.

Figure 4 is a plan view of the trap.

Figure 5 is an enlarged transverse vertical section as indicated by the line 5—5 in Figure 2.

Figure 6 is a side elevation of the tramway rope and suspended rabbit, with the position of the motor indicated.

Figure 7 is a vertical sectional view showing one of the pulley assemblages and rabbit hanger, the cables being in cross section.

Figure 8 is a side elevation of one of the pulley assemblages employed at the curved ends of the track.

40 Figure 9 is a plan view of the drive wheel and motor shaft.

In the drawings the numeral 10 indicates a continuous race track, 11 the fence at the inner side of the track and 111 the fence at 45 the outer side. A motor cable 12 travels on one of a pair of vertical pulleys 13, 14, disposed along the sides of the track, and about horizontal pulleys 113, 114, at the curved ends of the track. Above the pulleys 13 and 14 is 50 positioned a laterally disposed roller 17 to

prevent the cable from jumping from the pulleys, said roller turning on angle spindles 18. The numeral 15 indicates a stud shaft on posts 16, rising from the fence 11. The numeral 115 represents the angle spindle for 55 the horizontal pulleys 113, 114, said spindle being on posts 116.

A tramway cable 19 rests on and frictionally engages the pulleys 14, and passes about the pulleys 114. On said cable is a hanger 60 20 from which a mechanical rabbit 21 is suspended by cords or wires 22, having interposed therein suspension springs 23.

On the motor shaft 25 of a motor 24 is a bevel pinion 26 meshing with a bevel pinion 65 27 turning in the motor frame 28, said frame having sheaves 29 about which the cable 12 runs, said cable having also a bend about the drive pulley 30 in fixed relation to the driven pinion 27.

An opening in the fence 11 is provided and a trap is arranged at said opening into which the traveling rabbit may be caused to move. The numerals 31, 131, represent gate posts. To the post 131 is secured a gate 32 by hinges 70 75 33 also secured to the post 131. A spring 38 at the inner side of the gate 32 is fastened to post 131 and its free end is slidably engaged in a keeper 34. A latch 35 is disposed at the outer side of the gate and is subject 80 to a latch spring 135. The latch 35 is pivoted between its ends to brackets 36, and its free end 235 is formed with a tooth engageable with a rack 37 on post 131. A trigger 39 in the trap gate is provided and extends 85 through said gate, and has its short arm 40 outside of the gate. Said trigger is pivoted vertically as at 41 to the gate. When the gate 32 is swung open to the position shown 90 in Figures 2, 3 and 4, it is disposed as a barrier in the path of travel of the rabbit 21 when said rabbit travels in the normal path. Upon the rabbit encountering the gate 32, constituting a barrier to the further progress of the 95 rabbit, said rabbit is deflected laterally into the trap 43, which may be defined by an enclosure 42 indicated in dotted lines in Figure 2. The trigger 39 when the gate 32 is open 100 extends transversely of the path of travel of

the rabbit, as indicated in full and dotted lines in Figure 4.

The rabbit striking the trigger 39 will cause the short arm 40 to disengage the latch 35 so that the spring 135 causes the spur or tooth 235 to disengage the rack 37, whereupon the spring 38 which normally tends to close the gate will draw the gate inwardly into the plane of the gate posts 31, 131, so that 10 the rabbit thereby disappears. In the entering of the rabbit into the trap 43, the wires 22 and springs 23, constituting a flexible support, yield and permit of the rabbit moving laterally into the trap 43.

15 In order that the rabbit may be caused to travel through more than one circuit of the track, we provide means to cause the rabbit to travel outside of the gate 32 without encountering said gate or the trigger 39. For 20 the purpose indicated, those pulleys 213 and 214 adjacent the gate post 31 are carried on a slideable rod 34, movable transversely in a sleeve 45 on a post 216. The slideable rod 44 is pivoted to a vertically disposed lever 46 25 fulcrumed between its ends as at 47 on brackets 48 on post 216. To the lower end of said lever 46 is attached a horizontal operating rod 49 movable in a sleeve 50 below the track surface, the operating rod 49 being pivotally secured at its inner end to a lever 51 so that the rocking of the lever will move rod 49 and thereby operate the lever 46 and cause 30 rod 44 carrying the pulleys 213 and 214 to be moved laterally. Above the pulleys 213, 214, 35 is a roller 217 on an angle spindle 218, rigid with rod 44. By moving rod 44 (see Figure 2) outwardly toward the center of the track 10, the pulleys 213 and 214 will be carried outwardly, thus rabbit 21 moves in a path 40 away from the normal path and will clear the gate 32 and its appurtenances.

The horizontal pulleys 113 are positioned at the curved ends of the track 10 with sufficient radius to occupy positions away from 45 the inner fence 11, affording a vision for the dogs at the ends of the track greater than would be the case if the cable 19 carrying the rabbit was caused to travel close to the fence 11.

50 In the trap 43 is disposed a pair of yieldable brake shoes 43 flaring at the end approached by the rabbit 21 and converging toward the opposite end. At the backs of the shoes 43 are buffer springs 44, the one series 55 of springs 44 abutting at one end against the shoes and at the opposite end against the fence 11, whereas the other series of springs in the arrangement shown abut at one end against adjacent shoe 43 and at the opposite 60 end against a backing plate 45.

It will be obvious from the foregoing that the gate 32 may be interposed as a barrier in the path of travel of the rabbit 21 to cause the same to be deflected into the trap 43, and 65 that the cable 19 in which the rabbit 21 is

suspended may be deflected by a movement of the lever 51 away from the position of the gate 32 to clear the same to permit travel of the rabbit about the track the desired number of turns.

We would state furthermore that while the illustrated example constitutes a practical embodiment of our invention, we do not limit ourselves strictly to the exact details herein illustrated, since, manifestly, the same can be considerably varied without departure from the spirit of the invention as defined in the appended claims.

We claim:

1. An apparatus of the class described, including an overhead carrying means, the combination of a race track, a lure to attract dogs and suspended over said track, from said carrying means at one side of the track, together with movable means adapted to be interposed in the path of travel of the lure to deflect the same laterally from the normal path of movement. 80

2. An apparatus of the class described, including the combination of a race track, a lure, overhead carrying means from which said lure is suspended over said track, and means at one side of the track adapted to intercept the path of movement of the lure. 90

3. An apparatus of the class described, including the combination of a race track, a lure, overhead carrying means from which said lure is suspended over said track, means at one side of the track adapted to intercept the path of movement of the lure, the suspension means for the lure being flexible so that the second mentioned means interposed in the path of movement of the lure will cause the same to move laterally inward and flex the suspension means. 95

4. An apparatus of the class described, including an overhead tramway cable, a lure suspended from said cable, movable means constituting a barrier and adapted to be disposed in the path of travel of the lure, and means to deflect said cable so that the lure will clear the barrier and pass the same without interception. 100

5. In an apparatus of the class described, including a track, an endless overhead motor cable extending about the track, a tramway cable, sheaves on which the second cable may travel, means to drive the first cable, said sheaves being turned by said first cable and serving to frictionally drive the second cable, 110 together with a lure suspended from the second cable. 115

6. In an apparatus of the class described, including a track, an endless drive cable extending about the track, a motor driven sheave for actuating said cable, a second cable, means to cause travel of the second cable by the first cable, and a lure supported by the second cable. 125

7. In an apparatus of the class described 130

having a track and about which a lure is adapted to travel, a trap for the lure, means to cause the lure to move laterally into the trap, and means to arrest the movement of
5 the lure in the trap.
